UNITED STATES PATENT OFFICE.

CHARLES R. LEAGUE, OF AHWAHNEE, CALIFORNIA.

WALL MOLD.

Application filed October 17, 1921. Serial No. 508,200.

To all whom it may concern:

Be it known that I, CHARLES R. LEAGUE, a citizen of the United States, residing at Ahwahnee, in the county of Madera and State of California, have invented a new and useful Wall Mold, of which the following is a specification.

This invention relates to molds and more particularly to a novel form of mold especially designed in the construction of concrete walls or the like.

The primary object of the invention is to provide an adjustable mold having means for supporting the same in an upright position, while the plastic material is being poured therein.

Another object of the invention is to provide a mold which may be disassembled to permit of its being moved from place to place in the construction of a wall.

A still further object of the invention is to provide a mold wherein the side walls thereof are provided with ribs to engage the upper edges of a concrete structure to support the side walls of the mold in a vertical position.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:—

Figure 1 is an end elevational view of a mold constructed in accordance with the present invention.

Figure 2 is a side elevational view of the same.

Figure 3 is a plan view of the core forming a part of the mold.

Referring to the drawings in detail, the mold includes side members 5 and 6 respectively, the same being formed of suitable sheet metal and provided with inwardly extending ribs 7, formed adjacent to the upper and lower edges thereof, portions of the side walls extending below the ribs 7 as at 8 to provide guides for the mold, when the mold is positioned on a concrete structure, such as a section of a wall which has been completed.

Secured to the side wall 5 adjacent to the upper end thereof, are spaced keepers 9 which accommodate the arms 10 which support the apron 11 adapted to guide material to the interior of the mold during the use of the same.

Secured to the side walls 6 are the spaced angle irons 12 and 13 respectively, which angle irons provide trackways for the arm 14, which is provided with an inwardly extending portion 15 that is apertured to accommodate the rod 16 that supports the core of the mold, and which is indicated by the reference character 17. An auxiliary bracket 18 is secured to the inwardly extending portion 15 of the arm 14, and is also apertured to accommodate the rod 16 to insure the same being positioned vertically to support the core 17 in a true vertical position.

As shown, the lower extremity of the arm 14 is curved inwardly and upwardly as at 19 to engage over the angle iron 13, while the bar 20, which is curved inwardly and downwardly moves over the angle iron 12, it being understood that the bar 20 is secured to the arm 14 to permit the arm to move longitudinally of the angle irons 12 and 13, but prevent lateral movement of the arm with respect to the angle irons.

The side walls 5 and 6 are held in their proper molding positions, as by means of the adjustable clamp which embodies an arm 21 formed with an operating lever 22, the lower end of the arm being designed to engage the wall 6 in any suitable and well known manner. The arm 23 which cooperates with the arm 21 is formed in sections, the section 24 thereof being provided with elongated openings 25 that accommodate the securing bolts 26 to permit the device to be used in building walls of various widths, it being understood that if it is desired to provide a greater distance between the arms 21 and 23, the bolts 26 are removed and placed in other openings of the section 24.

The section 24 is also formed with an operating lever 26, which is provided with suitable means to engage in the rack 27 so the levers 22 and 26 will be held in proper relation with each other to prevent movement of the arms 21 and 23 under the pressure of the plastic material poured between the walls 5 and 6.

In order that the arm 23 may be held in

close engagement with the wall 5, set screws 28 are provided, which set screws may be operated to cause the inner ends thereof to closely engage the wall 5, there being 5 provided a pivoted bolt 29, carried by the wall 5, which bolt extends through the arm 23 and secured by means of the winged nut 30, for holding the arm 23 to the wall 5.

The core 17 which forms an important 10 feature of the invention is preferably hollow and is provided with an integral bar 31 formed with an opening to accommodate the bolt 32 of the supporting arm 16, the bolt providing means for securing the core 15 to the arm 16.

Ribs 33 are formed on the walls 5 and 6 the ribs being formed with openings 34 to accommodate suitable bolts, whereby an end section, not shown may be secured at the 20 ends of the side walls 5 and 6 to form an end of a concrete wall, the end section acting to support the plastic material between the walls 5 and 6.

In the use of the mold, the side walls 5 25 and 6 are moved to their proper positions, the arms 21 and 23 being positioned to support the walls 5 and 6 in their vertical positions. The core 17 is now moved to a position between the walls 5 and 6 and 30 the plastic material poured between the core and walls 5 and 6.

It is obvious that when the plastic material sets, an inclined surface will be formed adjacent to the upper and lower 35 edges thereof, which inclined edges provide seats for the ribs 7, when the mold is removed and positioned on the portion of the wall formed by the mold during the process of increasing the height of the wall.

Having thus described the invention, what is claimed as new is:—

1. In a mold, separable side walls, pivoted means for holding the side walls in spaced relation with each other, angle irons secured to one of the side walls, an arm, means 45 carried by the arm and engaging the angle irons to permit of movement of the arm longitudinally of the side walls, said arm having an inwardly extending portion, a core supported by the inwardly extending 50 portion, and a removable apron supported adjacent to the upper edge of one of the walls.

2. In a mold, separable side walls, adjustable means for supporting the walls in 55 vertical position, a core associated with the side walls, means for supporting the core and permitting the same to be moved longitudinally of the side walls, and a removable apron carried by one of the side walls. 60

3. In a mold, separable side walls, pivoted arms engaging the side walls and adapted to secure the walls in their vertical positions, one of said arms including an upper section having elongated openings, bolts carried by the arm associated with the upper section for permitting adjustment of the arms with respect to the walls of the mold, and a removable apron carried by one of the walls. 65

In testimony that I claim the foregoing as my own, I have hereto affixed my signature in the presence of two witnesses.

CHARLES R. LEAGUE.

Witnesses:

IDA MAY BARKSHIRE,
LEE S. SEWARD.
